Attny.

UNITED STATES PATENT OFFICE.

VICTOR MAUCK, OF MERION, PENNSYLVANIA.

THERMOSTATICALLY-CONTROLLED VALVE.

Application filed April 29, 1927. Serial No. 187,590.

My invention is particularly applicable to heaters of the class described in my co-pending application (28-27) Serial No. 171,237 filed February 26, 1927 for Letters 5 Patent of the United States, and operative to maintain a body of water heated to a pre-determined temperature, by a main burner supplied with gas under control of a thermostatically operative valve arranged to minutely regulate a small volume of gas 10 passing to the burner and to temporarily permit the passage of a much larger volume of gas to the same burner when the temperature of said body of water falls below the predetermined degree at which the minimum 15 supply of gas is maintained. In such heaters, a momentary abnormal demand upon the gas supply in the neighborhood may diminish the gas pressure to such a 20 degree that the minimum flames are extinguished, and my present invention provides means for automatically relighting the ensuing flow of unconsumed gas, which flow is, of course, augmented by the continued 25 operation of the thermostatically controlled valve as the temperature of the water falls. The object aforesaid is attained by providing a pilot flame burner supplied through a bypass around the thermostatically controlled 30 valve which determines the supply of gas to the main burner, and associating with such pilot burner and its automatic controlling mechanism a diaphragm valve through which the supply of gas is delivered both 35 to the main burner and to the pilot burner; said diaphragm valve being normally held open by the gas flowing to the main burner, while the pilot burner is operative, but constructed and arranged to be closed by back 40 pressure of the gas to shut off the supply of gas to the main burner, as a consequence of the automatic shutting off of the supply of gas to the pilot burner orifice, by the valve herein claimed.

45 My invention includes the various novel features of construction and arrangement hereinafter more definitely specified, and particularly the construction and arrangement of a gas burner body to act as one element of a thermostatic couple; the other element of said couple being preferably a non-metallic rod having a negligible coefficient of expansion in comparison with that of said burner body; said couple being coordinately arranged to control the passage of gas 50 through a burner orifice, in accordance with the expansion and contraction of the burner body and to permit the flow of gas through said orifice while a flame is maintained thereat, and to stop the flow of gas through 55 said orifice when such flame is extinguished and not immediately relighted, and said burner body consequently cools. As above contemplated, such control of the passage of gas to a burner may be used to shut off the 60 supply of gas to another burner; but my invention is not limited to such use.

In said drawings; Fig. I is a plan view of a gas water heater of the thermostatically controlled type aforesaid, conveniently embodying my invention. 65

Fig. II is a vertical sectional view of said heater, taken on the line II, II in Fig. I.

Fig. III is a plan view of the main burner and its appurtenances. 70

Fig. IV is a fragmentary vertical sectional view, taken on the line IV, IV in Fig. III.

Fig. V is a side elevation of said main burner and its appurtenances as seen from the lower side of Fig. III. 75

Fig. VI is a fragmentary vertical sectional view of the diaphragm valve, showing its relation to the main burner and its appurtenances shown in Fig. V.

In said figures; the water container comprises the cylindrical metal shell 1 having the cold water inlet 2 and the hot water outlet 3 at the top thereof, and the combustion chamber 5 at the bottom thereof. The diaphragm 6 forms the bottom closure of the water space 7 in said container 1, and the top of said combustion chamber. The flue 10 has its lower end connected with said diaphragm 6, and extends to the outer atmosphere, through said water container, parallel 80 with, but eccentric to, the axis of said container shell 1.

The hollow oblate water spreader 11 is

mounted in eccentric relation with said diaphragm 6, and extending below the latter in said combustion chamber; having at its upper portion, in coaxial relation, an externally 5 screw threaded neck flange 12 surrounded by the internally and externally screw threaded fusible metal sleeve 13 extending in a corresponding opening surrounded by the flange 14 in said diaphragm 6. Said 10 spreader has, in coaxial relation therewith, but eccentric to said container, the socket 15, engaged with the lower end of the hot water riser pipe 16, which latter terminates a short distance above said diaphragm 6 and 15 through which the heated water, from said spreader, is delivered into said space 7. Said spreader also has the two diametrically spaced cold water inlet nozzles 20, at respectively opposite sides of said socket 15 and in 20 communication with the water space 7 through said spreader neck 12.

The water drain pipe 21 extends from the bottom of said spreader 11 to the exterior of said combustion chamber 5, where it is provided 25 with the drain cock 22 through which sediment may be withdrawn from said spreader. The collar 23 encircles said drain pipe 21 and is provided with the set screw 24 to secure it in adjusted position, as a support 30 for the main gas burner 26. Said main gas burner is a hollow horseshoe-shaped body, having the radially extending cross bars 27 forming axial bearings 28 embracing said drain pipe 21 and resting upon said 35 collar 23. The mixing tube 30 extends from said burner body 26 in eccentric tangential relation thereto, but in diametrical relation with said container 1 and combustion chamber 5, as best shown in Fig. II, and is slip 40 fitted over the gas supply tube 31. The arrangement is such that said burner 26 may be readily withdrawn and replaced laterally with respect to said pipe 21 and collar 23 which support it.

As indicated in Fig. I, the gas conduit 33 leading to said burner 26 has the automatically, thermostatically operative, valve 34 arranged to control it in accordance with the expansion and contraction of the thermostatic element in the tube 35 which is rigidly connected with said valve. Said tube 35 extends diametrically in the water space 7 in said container 1 between said flue pipe 10 and hot water riser pipe 16, and said valve 34 and tube 35 are detachably connected with said container shell 1 by the screw thread 36 on the valve casing engaging the spud 37 in said shell.

I find it convenient to provide said gas supply conduit 33 with the manually operative stop cock 39 leading to said conduit 31 between said automatic valve 34 and said burner 26; and also to provide the manually operative needle valve 40 in said conduit 31 65 between said stop cock 39 and said burner

26 to control the effective area of the gas inlet port within said conduit 31.

The construction and arrangement above described are such that after the gas is lighted at the main burner 26, the gas supply is automatically varied, by the operation of the thermostatically controlled valve 34, in accordance with the temperature of the water in the reservoir space 7, to maintain the mass of water in said space at a predetermined temperature, say, 170° F.; the supply of gas being automatically increased when hot water is withdrawn from the outlet 3 with consequent inflow of cold water through the inlet 2, and diminished as the water is raised to the predetermined temperature by the heat from said burner 26; the flames at the burner 26 being reduced to the minimum height when the temperature of the water is raised to the maximum. As aforesaid; when the flow of gas to the main burner 26 is thus reduced to the minimum by the operation of the valve 34; the flames 41 at the burner 26 are liable to be accidentally extinguished by momentary lessening of the pressure of the gas in said supply pipe 33 from any cause; for instance, by an abnormal demand upon the gas supply in the neighborhood of the heater, and although means are provided, as above described, whereby the flow of gas to the burner may be manually shut off; the structure described does not include any means for apprising the user that the flames 41 has been thus extinguished at the main burner 26 and that the gas is flowing therethrough unconsumed and with increasing volume.

Therefore, in order to maintain the main burner 26 operative under such abnormal conditions I provide means to relight it automatically, including the pilot burner 42, which is supplied with gas independently of said valve 34, so that the pilot flame 43 may remain lighted when the flames of the main burner are extinguished; and provide, in coordinated relation with both the main burner 26 and said pilot burner 42, means for automatically shutting off the supply of gas to both, if and when the flames of both of said burners are accidentally extinguished.

Said pilot burner 42 is formed in the metal of the body of said burner 26, by drilling the latter; the pilot burner orifice 44 communicating with the valve casing seat 45 which is a cylindrical opening in the outer side wall of said burner body 26 in coaxial relation with the cylindrical recess 46, in the opposite inner wall, which forms a part of said valve casing seat and is provided with the pilot burner supply inlet 47 in communication with the supply conduit 48.

The thermostatic valve casing 50 which is fitted to said socket and forms a passageway for gas from said pilot inlet 47 to said pilot orifice 44, is cup-shaped, having two external

cylindrical zones at opposite ends thereof, respectively fitted in said seat openings 45 and 46, and has the intermediate internal annular valve seat 51. Said casing has its 5 rim end internally screw threaded at 52 and has the gas inlet ports 53 and valve stem bearing 54, at its other end. The gas is directed from said casing 50 into said pilot burner 42 through the restricted passageway 55, and air is admitted to said burner orifice 44 through the notch 56 in the side thereof, so that said burner is of the Bunsen type. The puppet valve 58 is fitted to said seat 15 51 and has the axial stem 59 fitted to said bearing 54. The spring 60 encircling said stem 59 tends to thrust said valve off its seat. The externally screw threaded bushing 61 is fitted to said rim thread 52 and has the coaxial cylindrical bearing 63 for the 20 thermostatic element 64, arranged to hold such element in coordinate relation with the coaxial abutment 66 on said valve, opposite said stem.

The opposite end of said thermostatic element 64, (which is preferably a ceramic or carbon rod having a coefficient of expansion which is practically negligible in comparison with that of the metal of the burner body 26, within the range of temperatures to 25 30 which the thermostatic couple are subjected in such embodiment,) is supported in the abutment 68, which is cast in unitary relation with the burner body 26 and internally screw threaded to engage the abutment 35 plug 69 which has the coaxial cylindrical bearing 70 for said thermostatic element 64 and the coaxial abutment 71 which bears against the end of said element 64 when the device is calibrated as shown in Fig. IV. It 40 is to be understood that by axial adjustment of said abutment plug 69, the temperature at which said valve 58 is operative may be variably predetermined. That is to say, the temperature of the burner body 26, (which 45 forms one element of the thermostatic couple, of which the other element is the rod 64,) at which said valve 58 is automatically opened and closed, is variably determinable by axial adjustment of said abutment plug 69. However, I prefer to thus coordinately calibrate 50 said thermostatic couple with said valve at the factory and to prevent disturbance of such adjustment thereafter, by rigidly connecting said plug 69 with the abutment 68 by 55 solder indicated at 73 in Fig. IV. However, it is to be understood that such solder or other means for sealing the adjustable plug 69 in its adjusted position, may be removed to permit withdrawal of said plug whenever 60 such withdrawal is necessary for repairs or otherwise.

It is to be understood that the thermostatically controlled valve 58, as above described with reference to Fig. IV, is operative to control the supply of gas to the 65 burner 42, without regard to the source of supply of the gas, which is supplied through the inlet 47 from the conduit 48. However, said conduit 48, which is preferably a flexible metal tube, extends to the casing 75 of 70 the plug valve 76. Said valve casing 75 is attached to the cover 77 of the diaphragm valve casing 78, and has the gas passage 79 leading from the chamber 80, in said cover 77, above the diaphragm 82, to said 75 pilot burner 42, and has the gas vent 83 opening directly to the atmosphere. Said valve 76 has the port 84 and may be manually turned to vary the flow of gas from said chamber 80 to the pilot burner, or to open 80 said vent 83 and thus relieve the diaphragm 82 of gas pressure above it, when the pilot burner is closed.

Said diaphragm valve casing 78 has the passageway 85 leading to said gas pipe 33, 85 leading to the main burner 26, and gas for both burners is supplied through the pipe 86 in communication with the passageway 87 in said casing 78, terminating in the seat 88 for the diaphragm valve 90. Said valve 90 is 90 adapted to close said passageway 87 and shut off the supply of gas to the main burner 26 whenever the pressure above said diaphragm 82 equals the pressure below it, which is when said pilot burner valve 58 is 95 closed. However, when either said valve 58 or the vent 83 is open, said diaphragm 82 is relieved of back pressure of the gas above it, and is lifted and upheld by the gas flowing through the passageway 77 to the main 100 burner 26; thus permitting such supply of gas to said burner 26, to be variably controlled by the thermostatic valve 34 as above described.

Said valve 90 has the "bleed" port 91 continually permitting the passage of gas for the pilot flame 43 when the pilot valve 58 is open. However, when said valve 58 is closed by the operation of the thermostatic couple 26, 64 as above described, the gas 105 pressure above the diaphragm 82, in the chamber 80, becomes equal to that below said diaphragm, and the diaphragm valve 90 closes upon its seat 88.

Said gas controlling devices operate as 110 follows: The adjusting plug 69 in the abutment 68, shown in Fig. IV, may be set so that the relative position of the thermostatic rod 64 is such that said valve 58 is closed at 400° F., but opened at any higher 115 temperature, by the spring 60 which encircles the valve stem 59 and continually tends to thrust said valve off its seat. The stop cock 76 and vent 83 of the valve casing 85 being opened, gas is supplied from the 120 pipe 86 through the diaphragm valve casing 78, pipe 33, valve 34, etc., to the burner 26, and may be manually ignited at the latter. Combustion of gas at the main burner 26 immediately heats the latter above 400° F., 125 130

so that it expands, whereas, the thermostatic rod 64 does not, and with the effect of permitting the valve 58 to be thrust off its seat by the spring 60, and the gas issuing from the pilot burner 42 is thereupon ignited by the flames 41 of the main burner 26. Thereafter, momentary diminution of the gas pressure, which may be sufficient to extinguish the flames 41 of the main gas burner 26, fails to extinguish the pilot flame 43 which is separately supplied as aforesaid, through the conduit 48 which forms a bypass around the thermostatic valve 34 which separately controls the supply of gas to said main burner. Consequently, when the normal gas pressure is restored, the gas escaping through the orifices 94 of the burner 26 is relighted in flames 41 by the pilot flame 43. Similarly, if said pilot flame 43 be accidentally extinguished, while the main burner flames 41 are present, the gas issuing from said pilot burner orifices 44 is relighted by said flames 41. However, if both the flames 41 and 43 be accidentally extinguished the temperature of the burner body 26 immediately falls to 400° F., with the effect of closing the pilot burner valve 58 which causes the back pressure of gas from the main supply pipe 86 through the orifice 91 in the diaphragm valve 90, to accumulate above the diaphragm 82 in the chamber 80 and thus permit said diaphragm valve 90 to close upon its seat 88 and thus shut-off the supply of gas to the burner 26.

Thereupon, to relight the burner the valve 76 may be turned 90 degrees counter-clockwise from the position shown in Fig. VI, to open said vent 83, thus releasing the gas pressure above the diaphragm 82; whereupon, said diaphragm valve 90 is opened by the gas pressure from the supply pipe 86 and the gas issuing through the orifices 94 of the main burner 26 may be manually relighted in flames 41. The consequent heating of the main burner 26 reopens the pilot burner valve 58 and restores the pilot burner flame 43 as above described.

Although I prefer to provide means, including the abutment plug 69 above described, for changing the relative position of the thermostatic elements 26 and 64, it is to be understood that said elements may be otherwise calibrated or may be made of predetermined standard length, and such adjusting means be omitted. Moreover, although I find it convenient to provide the spring pressed valve 58 for controlling the supply of gas to the pilot burner 42, it is to be understood that the pilot burner orifice 58 may be otherwise located and arranged to be closed by the difference in coefficients of expansion of the burner body 26 and the thermostatic element 64.

Therefore, I do not desire to limit myself to the precise details of construction and

arrangement herein set forth, as it is obvious that various modifications may be made therein without departing from the essential features of my invention, as defined in the appended claims.

70

I claim:

1. In a gas burner, the combination with a hollow metal body, forming a thermostatic element, which is a gas conduit leading to a burner jet orifice; of a valve arranged to control the flow of gas through said orifice; spring means normally tending to maintain said valve in open position; and a non-metallic thermostatic element, directly engaging said valve and coordinated with said hollow body as a thermostatic couple, arranged to control said valve, in accordance with the temperature of said hollow body.

2. A thermostatic couple, comprising two bodies having different coefficients of expansion; one of said bodies forming a gas burner jet orifice; valve means arranged to control said orifice in accordance with the expansion and contraction of said burner body; a spring normally tending to open said valve, when said burner body is heated by a flame at said orifice; said couple being coordinately arranged to shut said valve, against the action of said spring, when said flame is extinguished and said burner body consequently cooled.

3. In a gas burner, the combination with a single hollow metal body, forming a thermostatic element, and having a main gas supply inlet, a plurality of main gas burner orifices, in communication with said main inlet, a separate pilot gas supply inlet, a pilot gas burner orifice in communication with said pilot inlet, a valve seat in communication with said pilot inlet and pilot orifice, and an abutment in spaced relation to said seat; of a valve fitted to said seat and arranged to control the passage of gas to said pilot burner orifice; a spring tending to open said valve, from its seat; a thermostatic element supported by said abutment and arranged to normally hold said valve closed; and an adjustable abutment plug, movable to relatively calibrate said hollow burner body, with said other thermostatic element, as a thermostatic couple, and variably predetermine the temperatures at which said valve may be automatically opened and closed.

4. In a gas burner, the combination with a hollow metal body, forming a thermostatic element and having a main gas inlet and jet orifices in communication with said inlet, a separate pilot gas supply inlet, a valve casing socket local to said pilot inlet, a pilot gas burner orifice, in communication with said socket, and an abutment in spaced relation to said socket; of a valve casing fitted to said socket and forming a passageway

- for gas from said pilot inlet to said pilot orifice, and a valve seat; a valve fitted to said seat; a spring, in said valve casing, tending to lift said valve off its seat; and a 5 thermostatic element supported by said abutment and arranged to normally hold said valve closed.
5. In a gas burner, the combination with a hollow metal body, forming a thermos- 10 static element and having a main gas inlet and jet orifices in communication with said inlet, a separate pilot gas supply inlet, a valve casing socket local to said pilot inlet, a pilot gas burner orifice, in communication 15 with said socket, and an abutment in spaced relation to said socket; of a valve casing fitted to said socket and forming a passageway for gas from said pilot inlet to said pilot orifice, and a valve seat; a valve fitted to 20 said seat; a spring, in said valve casing, tending to lift said valve off its seat; a thermostatic element supported by said abutment and arranged to normally hold said valve closed; and a screw plug in said abut- 25 ment, adjustable to relatively calibrate said thermostatic elements, as a thermostatic couple, and variably predetermine the tem- 30 peratures at which said valve may be automatically opened and closed.
6. In a thermostatic valve structure, a cup-shaped casing having external cylindrical zones, at opposite ends thereof, and an intermediate internal annular valve seat; said casing having its rim end internally 35 screw threaded, and having a gas inlet and a valve stem bearing at the other end; of a puppet valve fitted to said seat and having an axial stem fitted to said bearing; a spring encircling said stem and tending to thrust 40 said valve off its seat; an externally screw threaded bushing fitted to said rim thread and having a coaxial cylindrical bearing for a thermostatic element, arranged to hold such element in coordinate relation with 45 said valve.
7. In a thermostatic valve structure, a cup-shaped casing having external cylindrical zones, of different diameters, at opposite ends thereof, and an intermediate internal 50 annular valve seat; said casing having its rim end internally screw threaded, and having a gas inlet and a valve stem bearing at the other end; of a puppet valve fitted to said seat and having an axial stem fitted to 55 said bearing; a spring encircling said stem and tending to thrust said valve off its seat; an axial abutment on said valve, opposite to said stem; an externally screw threaded bushing fitted to said rim thread, and having a coaxial cylindrical bearing for a 60 thermostatic element, arranged to hold such element in coordinate relation with said valve, against said abutment.
8. In a gas burner, the combination with 65 a hollow cast metal body having a gas jet orifice and an abutment; of a thermostatic element bearing, axially adjustable in said abutment; a thermostatic element mounted in said bearing; and a valve in cooperative relation with said thermostatic element, and 70 arranged to control the flow of gas to said orifice; said bearing being adjustable to vary the temperature at which said valve is operative.
9. The combination with a main gas 75 burner and a pilot gas burner, in cooperative relation; of a thermostatic couple and arranged to control said pilot burner in accordance with the temperature of said main gas burner; means arranged to supply gas 80 to both burners, including a valve casing having gas outlets, leading to the respective burners, and a common gas inlet; a flexible diaphragm in said valve casing between said gas outlets, and having said gas 85 inlet upon one side thereof; a valve carried by said diaphragm, arranged to control the passage of gas through the respective casing outlet to said main burner; and a constantly open bleed port leading from said gas inlet to the casing outlet leading to said pilot burner; whereby said diaphragm valve is normally held open, by the pressure of gas from said inlet, to permit the supply of gas to said main burner, when said pilot 90 burner is open; but said diaphragm valve is closed, to shut off the gas to said main burner, when said pilot burner is closed.
10. In a gas burner, the combination with a hollow metal body, forming a thermos- 100 static element, which is a gas conduit leading to a burner jet orifice; of a valve arranged to control the flow of gas through said orifice; spring means normally tending to maintain said valve in open position; and another thermostatic element, continually directly thrusting said valve toward its closed position and coordinated with said hollow body as a thermostatic couple, arranged to control said valve in accordance with the temperature of said hollow body.
11. The combination with a main gas burner and a pilot gas burner, in cooperative relation; of a non-metallic thermostatic element directly exposed to the atmosphere surrounding said main gas burner and coordinated with said main gas burner as a thermostatic couple and arranged to control said pilot burner in accordance with the 115 temperature of said main burner; means arranged to supply gas to both burners, including a valve casing having gas outlets, leading to the respective burners, and a common gas inlet; a flexible diaphragm in 120 said valve casing between said gas outlets, and having said gas inlet upon one side thereof; a valve carried by said diaphragm, arranged to control the passage of gas through the respective casing outlet to said 125

main burner; and a constantly open bleed is open; but said diaphragm valve is closed, port leading from said gas inlet to the cas- to shut off the gas to said main burner, when 10 ing outlet leading to said pilot burner; said pilot burner is closed. whereby said diaphragm valve is normally In testimony whereof, I have hereunto 5 held open, by the pressure of the gas from signed my name at Conshocken, Pennsyl- said inlet, to permit the supply of gas to vania, this fourth day of April, 1927. said main burner, when said pilot burner VICTOR MAUCK.
